UNITED STATES PATENT OFFICE.

HIRAM H. SPONENBURG, OF GURNEE, ILLINOIS, ASSIGNOR, BY MESNE ASSIGNMENTS,
TO OTTO R. BARNETT, OF CHICAGO, ILLINOIS.

RAIL-ANCHOR.

1,350,677.

Specification of Letters Patent. Patented Aug. 24, 1920.

Application filed October 3, 1919. Serial No. 328,254.

To all whom it may concern:

Be it known that I, HIRAM H. SPONENBURG, a citizen of the United States, residing at Gurnee, in the county of Cook and State 5 of Illinois, have invented certain new and useful Improvements in Rail-Anchors, of which the following is a specification.

My invention relates to a rail anchor device for resisting the tendency of railroad 10 rails to creep longitudinally and has for its primary object to provide a novel one-piece anchor device which will maintain a firm grip on the rail, which may be readily applied to rails having base flanges of different widths or contours, and which may be manufactured at a minimum cost.

A more specific object of the invention is to provide a novel one-piece device which 15 may be made from a flat strip of spring metal by bending one end of the strip to form a loop which will yield to permit the application of the device to rails having base flanges of different widths, the loop being formed so as to provide an overhang which 20 extends over the upper edge of the base flange in a manner to hold the body of the device firmly against the under surface of the rail base.

The invention has for further objects such 25 other normal construction relating to devices of the above character as will be hereinafter described and claimed for accomplishing the above mentioned objects and such other incidental objects as may be seen 30 from the following specification.

The invention is illustrated in certain preferred embodiments in the accompanying drawings, wherein—

Figure 1 is a plan view of a device constructed in accordance with my invention applied to the base flange of a railroad rail;

Fig. 2 is a view in perspective of the rail anchor device;

Fig. 3 is a front view of the device shown 45 in Fig. 1 illustrating the manner in which the device is applied to the base flange of a rail;

Fig. 4 is a view similar to Fig. 1 illustrating a modified form of the device;

Fig. 5 is a view in perspective showing 50 the device illustrated in Fig. 1, applied to the base flange of a rail in its operative position; and

Fig. 6 is a vertical section taken on line 6—6 of Fig. 4.

55

Like characters of reference designate like parts in the several figures of the drawings.

Referring first to Figs. 1 to 4, inclusive of the drawings; 10 designates a railroad rail 60 and 11 one of the cross ties on which the rail is supported. The rail anchor shown in these figures is preferably made up from a piece of flat spring metal by bending one 65 end of the metal blank upwardly and inwardly to provide a jaw 12 having a lip 13 which fits over one edge of the rail base. The other end of the blank is bent upwardly from the body portion to form a loop 14, the downwardly extending portion 70 15 of which is adapted to bear against the opposite edge of the rail base when the device is in operative position. The lower edge of the free end of the loop 14 is preferably cut away so as to provide a relatively 75 narrow tongue 16 which extends through an opening 17 in the body 18 of the blank. The end of this lip is then bent upwardly 80 against the under surface of the body as shown at 19. The device is formed with a 85 downwardly extending flange 20 adjacent the loop 14 which bears against the tie. The jaw end 12 of the device preferably stands a short distance away from the tie so as to 90 permit a slight skewing action of the device, for example, to permit the jaw end 12 to move toward the tie, when the rail creeps longitudinally in a direction toward the tie. The front edge of the free end 15 of the 95 loop 14 and the rear edge of the jaw 12 are given a slight set inwardly to provide knife-edges 21—22 respectively, which will take a biting hold on the rail to increase its grip thereon. These knife-edges will automatically take a biting hold on the rail when the anchor is skewed by the longitudinal movement of the rail or they may, if desired, be embedded into the edge of the rail base when the device is applied.

The distance between the jaw 12 and inner face 15 of the loop 14 is normally less than the width of the rail base to which the device is intended to be applied so that the loop portion will be strained when the device is applied to the rail. When the device is in its operative position, the inner 100 105

face of the loop 14 constitutes a rail base engaging jaw. This portion of the loop being strained in application of the device to the rail stands at an angle with relation to the vertical edges of the rail base so as to provide an overhang which extends over the upper edge of the rail base. The spring pressure of this portion of the loop exerted against the edge of the rail, in addition to providing a firm frictional grip of the device on the base, adapted to resist the creeping pressure of the rail, also holds the body portion of the device up against the under surface of the rail base and minimizes the rocking action of the anchor. Such rocking action often results from the corner of the tie being rounded so that the tie abutting flange does not properly engage the tie, that is, for example, as when the lower edge only of the said flange bears against the tie. When applying the device to a rail, the jaw 12 is fitted over one edge of the base flange and the other end of the device is forced on to the opposite edge of the rail, the device being made of spring metal will flex to substantially the position shown in dotted lines in Fig. 3, during the application of the device. A crow-bar or other suitable device may then be positioned under the loop end of the anchor and this end raised to the full line position. When raising the anchor the free end 15 of the loop will yield to permit the loop to spring over the edge of the rail base as shown in full lines.

35 In Figs. 4, 5 and 6 I have shown a modification in which the loop end 25 of the anchor instead of being bent upwardly from the body 26 as shown in the preceding figures is bent downwardly as indicated at 27 so that the lower portion of the loop will bear against the tie. The free end 28 of the loop frictionally engages the edge of the rail base and takes a biting hold thereon in the same manner as the form of anchor shown in Figs. 1 to 3 inclusive. With the construction shown in this modification it is possible to dispense with the customary downwardly bent flange providing the tie abutment. The modified construction is otherwise substantially the same as that disclosed in the previous figures and has been given corresponding reference characters.

I claim:

1. A rail anchor comprising a rail base embracing member formed at one end with a jaw for engaging one edge of the rail base and at the other end with an upwardly extending loop providing a jaw for engaging the opposite edge of the rail base; said loop being adapted to yield to permit the application of the device to the rail and exerts a spring pressure against the vertical edge of the rail when the device is applied to its operative position.

65 2. A rail anchor comprising a rail base

embracing member formed at one end with a jaw for engaging one edge of the rail base and at the other end with an upwardly extending loop providing a jaw for engaging the opposite edge of the rail base; said loop being strained during the application of the device to the rail so as to exert a spring pressure against the vertical edge of the rail base and projects over the upper edge of the rail base when the device is in its applied position. 75

3. A rail anchor comprising a rail base embracing member formed at one end with a jaw for engaging one edge of the rail base, an upwardly extending loop providing a jaw for engaging the opposite edge of the base, and a tie abutting flange; said loop being adapted to yield to permit the application of the device to the rail and exerts a spring pressure against the vertical edge of the rail when in its operative position. 80

4. A rail anchor comprising a rail base embracing member formed at one end with a jaw which fits over one edge of the rail base and at the other end with a loop, the free end of which extends downwardly and engages the vertical surface of the opposite edge of the rail base with spring pressure; the said loop being adapted to yield to permit the application of the device to the rail and normally projects over the edge of the rail base to maintain the device in its applied position. 95

5. A rail anchor comprising a rail base embracing member formed at one end with a jaw which fits over one edge of the rail base and normally stands out of contact with the tie and is formed at the other end with a loop the free end of which extends downwardly and engages the vertical surface of the opposite edge of the rail base with spring pressure; the said loop being adapted to yield to permit the application of the device to the rail and normally projects over the edge of the rail base to maintain the device in its applied position. 100 105

6. A rail anchor made from a flat piece of spring metal, the flat side of which bears against the under surface of the rail base, formed at one end with a jaw which engages one edge of the rail base and at the other with a loop which engages the opposite edge of the rail base and normally overhangs the edge with which it engages; the body of said anchor being formed with a slot and the lower portion of the free end of said loop being formed with a foot which extends through said slot and engages the under surface of said body. 115

7. A rail anchor comprising a rail base embracing member formed at one end with a jaw which fits over one edge of the rail base and at the other end with a loop the free end of which extends downwardly and engages the vertical surface of the opposite 120 125 130

edge of the rail; the device being formed with a tie abutting foot adjacent one end thereof so that the creeping pressure of the rail will tend to skew the anchor to increase 5 its grip on the rail.

8. A rail anchor comprising a rail base embracing member formed at one end with a jaw which fits over one edge of the rail base and at the other end with a loop the 10 free end of which extends downwardly and engages the vertical surface of the opposite edge of the rail; the edges of said loop and jaw being formed with projections adapted to be embedded in the rail base.

15 9. A rail anchor comprising a rail base

embracing member formed at one end with a jaw which fits over one edge of the rail base and at the other end with a loop the 20 free end of which extends downwardly and engages the vertical surface of the opposite edge of the rail; the device being formed with a tie abutting foot adjacent one end thereof so that the creeping pressure of the rail will tend to skew the anchor to increase 25 its grip on the rail and the edges of the said jaw and free end of said loop being formed with sharp edges adapted to take a biting hold on the rail.

HIRAM H. SPONENBURG.
